Patented Jan. 2, 1912.

UNITED STATES PATENT OFFICE.

THEODORE KARGAU, OF WARREN, OHIO, ASSIGNOR TO THE PEERLESS ELECTRIC COMPANY, OF WARREN, OHIO, A CORPORATION OF OHIO.

CENTRIFUGAL SWITCH FOR ALTERNATING-CURRENT MOTORS.

1,013,780.

Specification of Letters Patent.

Patented Jan. 2, 1912.

Application filed February 2, 1911. Serial No. 606,148.

To all whom it may concern:

Be it known that I, THEODORE KARGAU, of Warren, in the county of Trumbull and State of Ohio, have invented certain new 5 and useful Improvements in Centrifugal Switches for Alternating-Current Motors; and I do hereby declare the following to be a full, clear, and exact description of the invention, such as will enable others skilled 10 in the art to which it appertains to make and use the same.

The object of this invention is to provide improved, simple and highly efficient means for opening the circuit of the starting coils 15 of an alternating motor after the rotor has attained the desired velocity.

Briefly outlined, the invention, which is specially designed for fan motors embodies 20 brushes which are yieldingly held in contact with the inner surfaces of segments of the commutator, but which are themselves carried by the armature shaft; and these brushes will, when the desired velocity has been attained, be moved inwardly toward 25 the axial center of the commutator by the centrifugal action of weighted arms connected to the brushes, and thus open the circuit of the starting coils, such brushes, when the motor ceases to operate, being 30 automatically moved outwardly into contact with the segments of the commutator.

The invention will be hereinafter fully set forth and particularly pointed out in the claims.

35 In the accompanying drawings, Figure 1 is a side elevation, with parts broken away, Fig. 2 is a section on line 2—2, Fig. 1, with parts in dotted lines. Fig. 3 is a sectional view of a portion of the contact segments. 40 Fig. 4 is a detached perspective view of the brushes and their support. Fig. 5 is a face view of the portion of the contact segments shown in Fig. 3.

Referring to the drawings, 1 designates 45 two fixed contact members of an alternating motor, such members being shown in the form of opposite semi-circular segments 2 which are secured to a plate 3 of insulating material, which latter, in practice, is designed to be secured to the frame of the motor. I have shown connected to the two fixed members the windings of a two pole motor, that is to say, two starting coils. One end of each of these coils will be connected 55 to one of the segments 2, and at their

other ends these coils will be connected to the line.

To the rotor, conventionally indicated at 5, is secured a contact plate 6, and to this contact plate are riveted or otherwise secured two pins 7 which are parallel with the shaft of the rotor. Upon these pins are pivotally mounted two brushes 8 which are designed to contact with the inner surfaces of the two segments. These brushes remain 65 in contact with the segments when the motor is running at low speed, and are held in that position by suitable springs, but according to my invention, after a predetermined speed is attained these brushes are 70 caused to move inwardly, toward the axis of the supporting plate 6 and thus cut out the starting coils. The means shown for accomplishing this result consists in providing the brushes 8 with hubs 9 which are 75 loosely journaled on pins 7, and forming such hubs with outwardly extending arms 10 of greater weight than the brushes, and to these arms 10 I connect springs 12, which latter are also connected to the contact plate 80 6. The brushes are held in engagement with the inner faces of the segment until the desired speed of the motor has been obtained. At this point the arms 10 are thrown outwardly, under centrifugal action, and the brushes are disengaged from the stationary member of the switch, or, 85 specifically, the segments.

Thus it will be seen that I have provided extremely simple and highly efficient means 90 for opening the circuit through the starting coils of the motor after the rotor has attained the desired speed.

I claim as my invention:

1. In a motor, the combination with the 95 terminals of starting coils, fixed segments with which they are connected; and a rotor, of brushes arranged within the segments and designed to normally engage the inner surfaces thereof, such brushes being carried 100 by the rotor, and means for yieldingly holding the brushes in contact with the inner faces of the segments, and means for moving the brushes inwardly toward the axial center of the rotor and out of contact with 105 the segments when the desired speed has been attained.

2. In a motor, the combination with the 110 terminals of starting coils, fixed segments with which such terminals are connected,

and a rotor, of a support carried by the rotor, brushes mounted on said support and designated to normally engage the inner surfaces of the segments, means for normally holding such brushes in such engagement, and means carried by such brushes for moving them inwardly toward the axial center of the rotor and out of contact with the segments when the desired speed has been attained.

3. In a motor, the combination with the terminals of starting coils, fixed segments with which such terminals are connected, and a rotor, of a connecting plate carried by such rotor, pins projecting from said plate paralleling the axis of the rotor, brushes having hubs mounted on said pins, said brushes being designed to normally en-

gage the inner faces of said segments, weighted arms extending outwardly from 20 said hubs, and springs connecting said arms to said connecting plate, said arms being designed to move outwardly under centrifugal action to cause the brushes to move inwardly toward the axial center of the 25 rotor and out of engagement with the segments when the desired speed has been attained.

In testimony whereof, I have signed this specification in the presence of two sub- 30 scribing witnesses.

THEODORE KARGAU.
